UNITED STATES PATENT OFFICE.

RUDOLPH G. MULLER, OF IRVINGTON, NEW JERSEY.

FUR-HAT-BLOCKING MACHINE.

Application filed November 17, 1927. Serial No. 233,825.

This invention relates to improvements in fur or felt hat blocking machines; and the invention relates, more particularly, to a novel arrangement and construction of means for actuating the block to predetermine the head-size and height of the crown of the hat undergoing blocking operations.

In hat blocking machines there is usually provided a brim clamping means and an adjustable expandible hat-block, and the mechanism for actuating the latter comprises means to elevate the hat-block to the desired degree to determine the height of crown to be produced and additional means to expand the hat-block to the degree necessary to determine the head-size of the hat. The general practice in hat-block machine design has been to provide independently manipulatable lever devices to respectively operate the hat-block elevating mechanism and the hat-block expanding mechanism. Such independent levers required the operator to make two distinct separate motions or operations in order to elevate and expand the hat-block, and by reason of the divergence of the respective levers, required the operator to stoop and lift each lever independently, thus adding considerably to the labor and slowing up the operations as a whole; furthermore, the arrangement required the holding of the elevator lever while pulling up the expanding lever with the result that an exceedingly arduous and tiring expenditure of effort was required, and the output of the machine in a given time was unduly limited.

It is the principal object of the present invention to provide a novel construction and arrangement of hat-block elevator and expanding levers including a means for so interconnecting the same together that the operator, by a single manipulation or movement is enabled to actuate both levers in automatically timed relation and by a natural movement calculated to avoid necessity for constant stooping and lifting. To such end the present invention provides a novel means in the general form of a single bell-crank lever, together with means for so coupling the same with the main elevator and expanding levers that properly timed operative movements are automatically transmitted to both said main levers when said bell-crank lever is actuated. The invention also has for

an object to provide means whereby the main levers are automatically held in actuated or operative positions, so that the operator's hands may be freed for the accomplishment of other work.

The invention has for a still further object to provide a single actuating means for the elevator and expanding levers of a hat-blocking machine, which nevertheless permits of the usual initial adjustment of said levers for selectively varying at will the height of crown and the head-size of hats undergoing the blocking operations.

Other objects of this invention, not at this time more particularly enumerated, will be clearly understood from the following detailed description of the same.

The invention is clearly illustrated in the accompanying drawings, in which:—

Figure 1 is a side elevation of a hat-blocking machine, the elevator and expanding levers of which are provided with the novel single actuating means made according to and embodying the principles of this invention, the said levers and single actuating means being shown in this view in normal initial position; Figure 2 is a fragmentary detail top plan view of said elevator and expanding levers and the single actuating means therefore; and Figure 3 is a view similar to that shown in Figure 1, but with the levers moved to operative positions by said single actuating means.

Similar characters of reference are employed in the above described views to indicate corresponding parts.

Referring now to said drawings, the reference character 5 indicates a suitable framework in the upper portion of which is supported the tub 6 within or over which is located any suitable form of brim-tongs or brim clamping devices 7 which are disposed around an expandible hat-block 8. Said brim clamping devices 7 and expandible hat-block 8 may be constructed and operated in the usual manner familiar to those skilled in the hat machinery art, and to this end the usual vertically reciprocable elevating rod 9 for raising the hat-block 8 to stretch the hat for the production of a desired height of crown and the usual vertically movable expanding slide 10 for operating expanding mechanism of the hat-block is provided. Pivoted to the

frame-work 5 is the usual banding-lever 11, which may be counter-balanced as shown, and to which may be selectively attached suitably sized banding rings 12.

5 The means for producing operative movements of the elevating rod 9 comprises a rock-shaft 13 to the outer end of which is fixed a lever plate 14 having a slot 15 concentric to the axis of said rock-shaft. Pivoted related to said rock-shaft 13 is an elevator lever 16 which extends across the face of said lever plate 14. Said elevator lever 16 is adjustably coupled with said lever plate 14 by means of an adjusting screw 17 which is rotatably mounted in a bearing 17' connected with the latter so that its threaded portion engages with an internally threaded block 18 connected with said elevator lever and having its rearward portion disposed to ride in the slot 15 of said lever plate 14. By manipulating the adjusting screw 17 the relation of the elevator lever 16 to the lever plate 14 may be varied to produce a greater or less movement of the latter according to the height to which it is desired to raise the hat-block 8 to in turn determine the crown height of the hat body being blocked, all in the manner already familiar to those skilled in the art. Fixed on said rock-shaft 13 is a lever arm 19 which is interconnected by link means 20 with a pivoted lift lever 21, the free end of which is pivotally connected with a coupling block 22 secured to said elevating rod 9.

35 The means for producing operative movements of the expanding slide 10 comprises a second rock-shaft 23 to the outer end of which is fixed a lever plate 24 having a slot 25 concentric to the axis of said rock-shaft 23. Pivoted related to said rock-shaft 23 is an 40 expanding lever 26 which extends across the face of said lever plate 24. Said expanding lever 26 is adjustably coupled with said lever plate 24 by means of an adjusting screw 27 which is rotatably mounted in a bearing 27' connected with the latter so that its threaded portion engages with an internally threaded block 28 connected with said expanding lever and having its rearward portion disposed to ride in the slot 25 of said lever plate 24. By 45 manipulating the adjusting screw 27 the relation of the expanding lever 26 to the lever plate 24 may be varied to produce a greater or less movement of the latter according to the degree of expansion desired to be produced in 50 the hat-block 8 to in turn determine the head-size of the hat body being blocked, also all in the manner already familiar to those skilled in the art. Fixed on said rock-shaft 23 is a lever arm 29 which is interconnected by link means 30 with one end of a lift lever 31 fulcrumed intermediate its ends by a link connection 32 supported by said elevator lift lever 21, and to the opposite end of which lift lever 31 is pivotally connected the slide 55 10 which is slidable on said elevating rod 9,

and which actuates the means for expanding and contracting the sections of said hat block 8.

70 The single actuating means for operating said elevator and expanding levers 16 and 26 in properly timed relation, comprises a bearing stud 33 mounted in a supporting bracket 34 suitably attached and located in connection with the frame-work 5. Mounted on said stud 33 to turn thereon is a bell-crank lever comprising the handle arm 35 and the crank-arm 36. Connected with said supporting bracket 34 as a stationary part thereof is an off-set abutment 37 having a stop-face 38 and a second stop-face 39. Said crank-arm 36 is provided with stop-nose 40 to engage said stop-face 38 of the abutment 37 to dispose said bell-crank lever in normal initial position, while the handle arm 35 is provided with a stop-nose 41 to engage said stop-face 39 of said abutment 37 to dispose said bell-crank lever in operated position. Said crank-arm 36 is pivotally interconnected with the free end of said elevator lever 16 by means of an intermediate link 42. Projecting laterally outward from the end portion of said crank-arm 36 is a stud 43, and slidably engaged with said stud 43 is a draw-link 44 having a slot 45 in which said stud 43 rides. The lower end of said draw-link 44 is pivotally attached to the free end of said expanding lever 26.

75 80 85 90 95 100 105 110 115 120 125 130 In operation, after a hat-body H has been engaged over the hat-block 8 and clamped by the brim clamping devices 7 and wet down with hot water in the usual manner (the adjustments for height and size having been previously made in connection with the hat-block elevating and expanding mechanism in the manner above referred to) the operator grasps the handle arm 35 and pulls the same forward to turn the crank-arm 36. The initial upward movement of the crank-arm 36 immediately acts through the link 42 to pull upwardly the elevator lever 16 whereby upward movement is imparted to the elevating rod 9 and transmitted to the hat-block 8. While such hat-block elevating movement is occurring, the stud 43 rides up the slot of the draw link 44 until it engages the upper end of said slot, whereafter continued turning or swinging movement of the crank-arm 36 is translated into upward drawing pull on said draw link 44 to in turn swing upwardly said expanding lever 26 to produce the expanding movement of the hat-block 8. The handle lever 35 is pulled forward to the limit of movement as determined by the engagement of the stop-nose 41 with the stop face 39 of the abutment 37. Before this limit of movement is reached the upper end of the draw link 44 will be carried across the dead center of pivotal movement of the crank-arm 36, so that as the handle lever 35 is brought to stopped position, the elevating and expand-

ing levers 16 and 26 will be automatically sustained or upheld in operative raised positions, whereupon the operator's hands may be released for the performance of other work. After the hat-body is stretched and blocked by the above described actuation of the hat-block 8, the banding lever 11 may be lowered to operatively engage the banding ring with the hat body, and the latter is ready to be hardened by application of cold water in the well-known way. After the hat-body has been hardened, the operator grasps the handle lever 35 and swings the same back to initial position, thereby releasing the elevating and expanding levers and returning the same to initial lowered position to in turn lower and contract the hat-block so that the blocked hat may be removed therefrom, and the next hat body applied thereto for a repetition of the described operations.

From the above description it will be obvious that the present invention provides a very simple and easily manipulated means for actuating the elevating and expanding levers of a hat blocking machine through a single power applying mechanism, thereby both reducing the labor required and saving time in carrying on hat-blocking operations.

It will be obvious that some changes may be made in the various arrangements and combinations of the several cooperating mechanisms, as well as in the details of the construction of the same, without departing from the scope of this invention as defined in the appended claims. Hence, I do not limit my invention to the exact arrangements and combinations as described in the foregoing specifications, nor do I confine myself to the exact details of the construction of the mechanisms and parts thereof shown in the accompanying drawings, and such description and showing is to be taken as illustrative and not in a limiting sense.

I claim:

1. In a hat-blocking machine having hat-block elevating mechanism including an elevator lever and a hat-block expanding mechanism including an expanding lever, a single manipulating means for actuating both said levers, comprising a pivoted bell-crank lever, a connecting link between said bell-crank lever and elevator lever, a draw-link connected with said expanding lever, and means providing a sliding pivotal connection between said draw-link and said bell-crank lever.

2. In a hat-blocking machine having hat-block elevating mechanism including an elevator lever and a hat-block expanding mechanism including an expanding lever, a single manipulating means for actuating both said levers, comprising a pivoted bell-crank lever, and means to independently connect said elevator lever and said expanding lever to and for actuation by said bell-crank lever.

3. In a hat-blocking machine having hat-

block elevating mechanism including an elevator lever and a hat-block expanding mechanism including an expanding lever, a single manipulating means for actuating both said levers, comprising a pivoted crank-arm, a connecting link between said crank-arm and said elevator lever, a draw-link pivotally attached to said expanding lever, means to provide a sliding pivotal connection between said draw-link and said crank-arm, a hand-lever for operating said crank-arm, and stationary stop means to determine the limits of movement of said crank-arm.

4. In a hat-blocking machine having hat-block elevating mechanism including an elevator lever and a hat-block expanding mechanism including an expanding lever, a single manipulating means for actuating both said levers, comprising a pivoted crank-arm, a connecting link between said crank-arm and said elevator lever, a draw-link pivotally attached to said expanding lever, said draw-link having a longitudinal slot, said crank-arm having a stud engageable in said slot of said draw-link, and a hand-lever for operating said crank-arm.

5. In a hat-blocking machine having hat-block elevating mechanism including an elevator lever and a hat-block expanding mechanism including an expanding lever, a single manipulating means for actuating both said levers, comprising a pivotal bearing means, a crank-arm mounted on said bearing means, said bearing means having a stop abutment engageable by said crank-arm to determine the normal initial position of the latter, a hand-lever for operating said crank-arm, said hand-lever being also engageable with said stop abutment to determine the operated position of said crank-arm, a connecting link between said crank-arm and said elevator lever, a draw-link connected with said expanding lever, and means to provide a sliding pivotal connection between said draw-link and crank arm.

6. In a hat-blocking machine having hat-block elevating mechanism including an elevator lever and a hat-block expanding mechanism including an expanding lever, a single manipulating means for actuating both said levers, comprising a pivotal bearing means, a crank-arm mounted on said bearing means, said bearing means having a stop abutment engageable by said crank-arm to determine the normal initial position of the latter, a hand-lever for operating said crank-arm, a connecting link between said crank-arm and said elevator lever, a draw-link connected with said expanding lever, means to provide a sliding pivotal connection between said draw link and crank-arm, and means to retain said crank-arm in operated position to hold said respective elevator and expanding levers in actuated positions.

7. In a hat-blocking machine having hat-

block elevating mechanism including an elevator lever and a hat-block expanding mechanism including an expanding lever, a single manipulating means for actuating both said levers, comprising a pivotal bearing means, a crank-arm mounted on said bearing means, said bearing means having a stop abutment engageable by said crank-arm to determine the normal initial position of the latter, a hand-lever for operating said crank-arm, a connecting link between said crank-arm and said elevator lever, a draw-link connected with said expanding lever,

means to provide a sliding pivotal connection between said draw-link and crank-arm, and means to retain said crank-arm in operated position to hold said respective elevator and expanding levers in actuated positions, said latter means comprising a stop abutment engageable by said hand-lever after said draw-link has crossed the dead center of movement of said crank-arm. 15 20

In testimony, that I claim the invention set forth above I have hereunto set my hand this 12th day of November, 1927.

RUDOLPH G. MULLER.
